Attorney.

UNITED STATES PATENT OFFICE.

WALTER E. BARTELS, OF CINCINNATI, OHIO.

ROOFING SHINGLE.

Application filed July 26, 1926. Serial No. 124,882.

My invention relates to roofing shingles and has particular reference to shingles of the flexible type.

The principal object of this invention is to provide a flexible shingle of asphalt slate type which may be applied to a roof in such a manner as to entirely obviate the possibility of curling or other displacement.

A further object of the invention is to provide a shingle of the character mentioned, in which the so-called shadow lines are of substantial thickness to give the appearance of massiveness to the roof construction and in which such shadow lines bear the same appearance as the surface of the shingle proper. In asphalt slate shingles as heretofore made and used in the construction of roofs, the end edges of such shingles which constitute the shadow lines, constitute a sectional thickness of the shingle itself and therefore such edges expose the raw asphaltatum of which the shingle is basically constructed, said exposed edges thus contrasting with the surfaces of the shingles which are provided with sand or small particles of rock of ornamental color and appearance.

Another object of the above invention, as above stated, is to overcome this faulty appearance of the roof and to produce shadow lines of increased thickness and mass.

Further objects will appear from the following detailed description thereof:

In the drawings:

Figure 1 is a perspective of a shingle constructed in accordance with this invention.

Figure 2 is a perspective of said shingle illustrating the method of its application to a roof.

Figure 3 is a perspective of a series of shingles as applied to a roof.

A shingle constructed in accordance with this invention consists of a strip of material 1 comprising a base of paper or felt impregnated with asphalt mastic upon which there are imbedded small particles of stone or sand 2, said features being of the usual construction known as asphalt slate shingles. The novel features of construction comprise the elongation of the strip so as to provide an underbent flange 3 of approximately one-half the length of the strip and a narrow up-

turned flange 4. The shingles provided with the flanges mentioned are applied to a roof as illustrated in Figures 2 and 3 of the drawings. The shingles being of flexible construction, in applying same the body of the shingle is lifted as shown in Figure 2 and nails 5 applied through the flange near the fold. The body of the shingle is then turned downwardly so as to rest upon the roof in the usual manner, and the next shingle is placed with the free edge of the flange 3 inserted below the upper flange 4 of the first shingle, as shown in Figure 3. The body of the second shingle is lifted in the same manner as was done in the first shingle and nailed at the same point, said nails passing through the first shingle, as shown in Figure 3 of the drawings. Subsequent shingles are applied in the same manner, each series of subsequent nails passing through the three shingles so that when the roof is constructed of shingles of the above described design each shingle is secured to the roof by means of three rows of nails, staples or other securing devices, one of which rows is near the bottom or exposed portion of the shingle, the other near the middle part thereof, and the third row at the upper end thereof. It will thus be seen that all shingles are rigidly secured and absolutely prevented from curling or warping.

By reason of the under-turned flange 3 construction, the shadow line edges 6 of the shingle are of turned construction and of double or slightly more than double thickness of material of which the shingles are made. As the entire surface of the shingle furthermore, may be covered with the ornamental sand or rock particles, the shadow line edges present the same ornamental appearance and thus add greatly to the beauty of a roof constructed of such shingles, both by reason of the comparative massiveness or thickness of the shadow line edges as well as their presenting a uniform appearance with the surface of the shingles themselves.

Having thus fully described my invention, what I claim as new and desire to secure by Letters Patent is:

A roofing shingle of flexible type, comprising a body portion, an underturned flange

at the lower end of said body portion, said flange being of substantially half the length of said body portion, and a short upturned flange along the upper end of said body portion, said lower flange being adapted to receive a line of nails adjoining the body portion, and said upper and lower flanges be-

ing arranged to interlock and being arranged to be so positioned with respect to the next higher shingle when laid, that the 10 line of nails through the lower flange of said higher shingle, will engage through the interlocking portions of the lower shingles.

WALTER E. BARTELS.
